UNITED STATES PATENT OFFICE.

FRED C. POLING, OF MENLO, IOWA.

DESIGN FOR A TIRE-LUG.

52,343.

Specification for Design. Patented Aug. 27, 1918.

Application filed February 13, 1917. Serial No. 148,449. Term of patent 3½ years.

To all whom it may concern:

Be it known that I, FRED C. POLING, citizen of the United States of America, and resident of Menlo, Guthrie county, Iowa, have invented a new, original, and ornamental Design for a Tire-Lug, of which the following is a specification.

The object of this invention is to provide a new and ornamental design for a tire lug.

My invention consists in the design for a tire lug, reference being had to the accom-

panying drawing, forming part thereof, in which—

Figure 1 is a plan of a tire lug illustrating the design, Fig. 2 is a side elevation and Fig. 3 an end elevation of the same.

I claim:

The ornamental design for a tire lug, as shown.

Signed by me at Des Moines, Iowa, this 9th day of February, 1917.

FRED C. POLING.
